DRINKING FOUNTAIN

Talman Horace Tanner, San Antonio, Tex.

Application March 29, 1955, Serial No. 35,269

Term of patent 14 years

(Cl. D67—4)

Fig. 1

I claim:

The ornamental design of a drinking fountain, as shown.
